TRANSMISSION LINE CIRCUIT

Nils E. Lindenblad, Rocky Point, N. Y., assignor
to Radio Corporation of America, a corporation
of Delaware

Application September 4, 1943, Serial No. 501,273

7 Claims. (Cl. 178—44)

1

The present invention relates to high frequency filter systems for connecting together one or more transmitters and receivers to a common antenna system and, more particularly, to such systems for use in pulse transmitting and receiving systems used in radio detecting and ranging.

An object of the present invention is the provision of a filter device for enabling the selective coupling of a transmitter and receiver to a common antenna system without requiring the use of mechanical switches.

Another object of the present invention is the provision of a filter network, the operating characteristics of which are controlled by the power applied thereto.

A further object of the present invention is the provision of a filter device for pulse transmitting and receiving systems.

Still a further object is the provision of an antenna and filter device for pulse transmitting and receiving equipment which utilizes no moving parts or mechanical switches for diverting the outgoing and incoming pulses to the appropriate transducer equipment.

Still a further object is the provision of a filter device, as aforesaid, particularly designed for use in systems utilizing crystal receivers.

Still a further object is the provision of a filter device, as aforesaid, in which the power consumption of the device is small.

Still another object is the provision of a filter circuit which utilizes low power trapping sparks for performing the switching operation.

The foregoing objects, and others, which may appear from the following detailed description, are attained in accordance with the principles of the present invention by providing a filter device between an antenna, a receiver and a transmitter, the filter device connecting the transmitter, receiver and antenna together in a bridge fashion. The bridge of the filter device utilizes a plurality of resonant structures having electrical discontinuities therein and which are so placed and so connected that when signalling potentials are applied thereto from the transmitter the electrical discontinuities are caused to break down and become conducting. The filter device thereby causes the energy from the transmitter to be conducted to the antenna but prevents its application to the receiver. When the transmitter ceases operation, the electrical discontinuities are restored and the signals picked up by the antenna are applied to the receiver. The electrical discontinuities are so placed that no received energy is permitted to flow to the transmitter circuit.

2

The present invention will be more completely understood by reference to the following detailed description, which is accompanied by a drawing in which transmission line TL is adapted to be connected from a suitable antenna (not shown) to the filter device of the present invention; transmission line TLT is adapted to be connected from a transmitter organization (not shown) to the filter device, while transmission line TLR is adapted to connect the receiver, which is likewise not shown, to the filter device. Transmission line TLT includes a hollow tubular outer shell 3 concentrically arranged about an inner conductor 4 and transmission line TL includes an outer shell 1 and a concentrically arranged inner conductor 2. Between transmission lines TL and TLT are connected two parallel branch concentric transmission lines 7 and 10. Transmission line 7 includes an outer shell 8 and a coaxially arranged inner conductor 9 and transmission line 10 has an outer shell 11 and an inner conductor 12. The ratio of the diameters of shells 1 and 3 to the inner conductors 2 and 4 associated therewith may be so chosen as to provide a characteristic impedance of the order of 70 ohms. Each of the branch transmission lines 7 and 10 may have the ratios of the inner and outer conductors so chosen as to provide a characteristic impedance of the order of 100 ohms. However, the present invention is not limited to the use of these values of impedance which are given only as illustration. TL and TLR may, for instance, be 50 ohms, in which case they match the branch lines.

Now, if it is assumed that the transmitter is in operation and the power pulse from the transmitter traveling along transmission line TLT arrives at the junction of transmission lines 7 and 10 with transmission line TLT at point A, the power pulse may then proceed along the two branch lines 7 and 10 to point F where they join with transmission line TL. Transmission line 7 at point B has connected thereto a low power spark trap 15 while transmission line 10 has connected thereto at point C a similar spark trap 16. Spark trap 15 includes an outer tubular shell 17 connected at one end to a shell 8 of transmission line 7 and an inner conductor 18 connected at one end to the inner conductor 9 of transmission line 7 at point B. The other end of shell 17 is closed by an end plate and the adjacent end of inner conductor 18 has interposed between it and the end plate a spark gap 19. Similarly, the spark trap 16 includes an outer shell 20 connected to outer shell 11 of transmission line 10 and an

inner conductor 21 connected at point C of conductor 12 of transmission line 10. The end of conductor 21, remote from point C, is connected to the closed end of shell 20 by a spark gap 22.

When the previously mentioned pulse from the transmitter arrives at points B and C on the transmission lines 7 and 10, spark gaps 19 and 22 break down thus directly connecting conductors 18 and 21 to the outer shells 17 and 20. Due to the quarter wave-length of these trap elements, points B and C assume a high impedance for the energy of the pulse and the power pulse thus proceeds along the branches as though there were no traps at all.

The transmission line TLR from the receiver is connected in a push-pull relationship to the two inner conductors 9 and 12 to transmission lines 7 and 10 at points D and E, that is, the outer shell 5 of transmission line TLR is directly connected at its upper end to conductor 12 of transmission line TL, while the inner conductor of transmission line 6 of conductor TLR is directly connected to conductor 9 of transmission line 7. In order to electrically free the end of the outer shell of transmission line TLR from ground, a quarter wave end portion 30 is surrounded by an outer shell 31 connected at point 32 to shell 5. Thus a high impedance is maintained between the upper end of shell 5 and the remaining outer shell structures of the filter device. In order to assure exact electrical symmetry across points D and E, point D has connected thereto a cylindrical conductor section 33 having the same diameter and length as the inner portion 30 of the outer shell 5 of transmission line TLR. This cylindrical conducting portion 33 is surrounded by an outer shell 34 to which it is connected at a point one quarter of the operating wavelength distant from point D.

Now, since the receiver line TLR is connected across the two branch transmission lines 7 and 10 at points equally distant over each parallel branch from junction A to the line TLT, there will be no potential difference across the receiver line TLR developed by the transmitted pulse. None of the pulse energy will therefore be dissipated in the receiver circuits. Conductor portions 30 and 33 act as quarter wave resonant shunts across the transmission lines 7 and 10 and dissipate none of the energy of the pulse.

It should be noted that the distance between junctions A and F is chosen to be equal to one wavelength. The connection between junctions A and F consists of two one hundred ohm lines in parallel. Such a combination does not directly match a 70 ohm line, but this does not matter since the length of the branches is equal to a multiple of a half wave. No matter what the impedance is at one junction, the same impedance will occur at the other junction, even if there are standing waves on the transmission line system.

Now the operation of the filter device when receiving a signal from the antenna will be considered. The spark gap trap circuits 15 and 16 have their spark gaps 19 and 22 deionized. Points B and C where the traps connect to the parallel branch lines 7 and 10 are thus of low impedance. The sleeve extension 30 of the receiving line TLR presents a low impedance at its mouth as if it were grounded since the distance from point E at the open end of the sleeve extension 30 is a half wavelength from point C where the low impedance is presented. Since point E is at low impedance the transmission line 10 at point F

presents a high impedance to energy arriving along transmission line TL and no received power will flow over transmission line 10. Instead, the incoming power will flow along transmission line 7 to point D where the inner conductor 9 of transmission line 7 is connected to the inner conductor 6 of transmission line TLR. The received energy will therefore be applied from the antenna to the receiver. Since spark trap 15 is located a distance of a quarter wavelength away from point D and presents a low impedance at point B, transmission line 7 at point D will present a high impedance to the flow of energy further along transmission line 7. Thus the passing of any energy from the antenna to the transmitter is prevented.

The trap circuits 15 and 16 become the most effective when the line elements have the highest characteristic impedance. This is due to the fact that the spark impedance is not zero and thus the highest impedance is obtained a quarter wave distant from the spark gaps when the transforming link, that is, the distance along the conductor between gap 19, for example, and point B has a characteristic impedance well above that of gap 19 itself because the characteristic impedance of a quarter wave transforming link forms the geometric mean of the impedances at its terminals.

It will be noted that the first quarter wavelength of conductor 6 within the shell extension 30 is given such diameter with relation to the shell 30 as to present a characteristic impedance of 100 ohms. The distance from point F through point D to a point on conductor 6 opposite 32 on the outer shell 5 being a full half wave, there will be no interruption in line matching between transmission line TL and transmission line TLR. Between point 32 on the transmission line TLR and the receiver, the transmission line may have an impedance of 70 ohms, or if another value is desired, an impedance matching circuit may be interposed.

While I have illustrated a particular embodiment of the present invention, it should be clearly understood that it is not limited thereto since many modifications may be made in the several elements employed and in their arrangement and it is therefore contemplated by the appended claims to cover any such modifications as fall within the spirit and scope of the invention.

Having now described the invention, what is claimed and desired to be secured by Letters Patent is the following:

1. A switching circuit adapted to be connected between a first and a second pair of transmission lines and including a pair of parallel transmission lines, each of said transmission lines including an outer shell conductor and an inner conductor, the conductors of said pair of transmission lines being connected in a parallel relationship to conductors of said first and second lines, the length of each of said pair of lines being one wavelength, means for connecting the conductors of a third transmission line in a push-pull relationship to inner conductors of said pair of lines at a distance equal to a quarter of the operating wavelength from the connection to the first transmission line, a quarter wave trap spark circuit connected across one of said pair of lines at a distance equal to one quarter of the operating wavelength from the other end and a quarter wave trap spark circuit connected across the other of said pair of lines at a distance equal to one half of the operating wavelength from said other end.

2. A switching circuit adapted to be connected between a first and a second pair of transmission lines and including a pair of parallel transmission lines, each of said transmission lines including an outer shell conductor and an inner conductor, the conductors of said pair of transmission lines being connected in a parallel relationship to conductors of the first and second lines, the length of each of said pair of lines being an even multiple of a half of the operating wavelength, means for connecting the conductors of a third transmission line in a push-pull relationship to the inner conductors of said pair of lines at a distance equal to a quarter of the operating wavelength from the connection to the first transmission line, a quarter wave trap spark circuit connected across one of said pair of lines at a distance equal to one quarter of the operating wavelength from the other end and a quarter wave trap spark circuit connected across the other of said pair of lines at a distance equal to one half of the operating wavelength from said other end.

3. A switching circuit adapted to be connected between an antenna transmission line and a transmitter transmission line, said circuit including a pair of line sections connected in parallel relationship at adjacent ends of said transmission lines, means for so coupling a receiver transmission line in push-pull relationship to a conductor of each of said pair of line sections that normally different impedances are presented to said line sections by each of the conductors of said receiver transmission line whereby said receiver is coupled to said line sections, and means responsive to energy from said transmitter to cause the conductors of said receiver transmission line to present the same impedance to energy on said pair of line sections whereby said receiver transmission line is not coupled to said antenna transmission line.

4. A switching circuit adapted to be connected between an antenna transmission line and a transmitter transmission line, said circuit including a pair of coaxial transmission line sections each having an outer shell and an inner conductor and connected in parallel relationship at adjacent ends of said transmission lines, the length of each of said pair of line sections being an even multiple of one-half wavelength, means for coupling a receiver transmission line in a push-pull relationship to the inner conductors of said pair of line sections, and means for causing the conductors of said receiver transmission line to present different impedances to energy on said pair of line sections whereby said receiver line is coupled to said antenna transmission line, and means responsive to energy from said transmitter for so unbalancing said line sections that the same impedance is presented by each of said conductors of said receiver transmission line to said line sections, whereby said receiver is uncoupled from said pair of line sections.

5. A switching circuit adapted to be connected between an antenna transmission line and a transmitter transmission line, said circuit including a pair of coaxial transmission line sections, each having an outer shell and an inner conductor and connected in parallel relationship at adjacent ends of said transmission lines, the lengths of each of said pair of line sections being one

wavelength, means for coupling a receiver transmission line in a push-pull relationship to said line sections, said receiver transmission line presenting the same high impedance to energy from said transmitter, and means for effectively connecting the inner conductor of one of said line sections to the outer shell at the point of connection of one of the conductors of said receiver transmission line, whereby the conductors of said receiver transmission line present different impedances to energy on said pair of line sections, whereby said receiver transmission line is coupled to said antenna transmission line.

6. A switching circuit adapted to be connected between a first and second transmission line, said switching circuit including a pair of parallel transmission line sections, each of said transmission line sections including an outer shell conductor and an inner conductor, the conductors of said pair of transmission line sections being connected in a parallel relationship to conductors of said first and second lines, the length of each of said pair of line sections being one wavelength, means for connecting the conductors of a third transmission line in a push-pull relationship to inner conductors of said pair of line sections at a point intermediate their ends, a pair of quarter-wave trap circuits each having a series spark gap therein, one of said trap circuits being connected across each of said pair of line sections, the point of connection of said trap circuits being so chosen that in the absence of energy above a predetermined value in said line sections, the conductors of said third transmission line present unequal impedances to said pair of transmission line sections whereby said third transmission line is coupled to said first transmission line, the point of connection of said trap circuits being further so chosen that in the presence of energy on said transmission lines above a predetermined value, said trap circuits cause the conductors of said third transmission line to present the same impedances to energy on said pair of line sections, whereby said third transmission line is uncoupled from said first transmission line.

7. A switching circuit adapted to be connected between an antenna transmission line and a transmitter transmission line, said circuit including a pair of line sections connected in parallel relationship to adjacent ends of said other lines, means for coupling a receiver transmission line in a push-pull relationship to a conductor of each of said pair of line sections, and means responsive to energy from said transmitter for causing the conductors of said receiver transmission line to present the same high impedance to energy from said transmitter, said energy responsive means including series spark gaps in quarter wave line sections so connected to said pair of line sections that when said gaps are non-conducting the conductors of said receiver line show different impedances to energy on said pair of lines whereby said receiver line is coupled to said antenna transmission line, said energy responsive means being further so connected to said pair of line sections that when said gaps are conducting the conductors of said receiver line present the same impedance to energy on said pair of lines whereby said receiver line is uncoupled from said antenna transmission line.
